UNITED STATES PATENT OFFICE.

WORTHY C. BUCKNAM, OF JERSEY CITY, NEW JERSEY, ASSIGNOR TO DAVIS-BOURNONVILLE ACETYLENE DEVELOPMENT COMPANY, OF PIERRE, SOUTH DAKOTA, A CORPORATION OF SOUTH DAKOTA.

CUTTING-TORCH.

1,097,526.

Specification of Letters Patent. Patented May 19, 1914.

Application filed July 14, 1911. Serial No. 638,431.

To all whom it may concern:

Be it known that I, WORTHY C. BUCKNAM, a citizen of the United States, and a resident of Marion, Jersey City, in the county of 5 Hudson and State of New Jersey, have invented certain new and useful Improvements in Cutting-Torches, of which the following is a specification.

This invention relates to metal cutting apparatus, in which the cutting is effected chemically by a jet of oxidizing gas, aided by a stream or streams of a combustible mixture, for raising the metal locally to a temperature at which it will be oxidized 10 rapidly by the oxidizing stream. The oxidizing gas is oxygen, and the combustible mixture is preferably composed of oxygen and acetylene.

In accordance with this invention I provide a torch which delivers heating and cutting jets all in alinement, two heating jets, consisting of a main, larger jet and an auxiliary, smaller heating jet, being delivered at opposite sides of the oxidizing jet and at different planes. By placing the heating jet orifices in different planes, the forward or main heating jet is delivered at a higher level or farther back toward the sources of supply than the following or auxiliary heating jet. In use the jets are caused to travel in line along the line of the cut, the larger and more remote heating jet being in front, the cutting jet following, and the smaller jet of combustible mixture last and burning inside the cut.

In the preferred embodiment of the invention the apparatus has a removable and replaceable tip, wherein are formed means for delivering the jet of cutting oxygen and 40 means for forming the combustible mixture and delivering it in larger and smaller jets at opposite sides of the cutting jet, all of the jet orifices being in alinement, and the heating jet orifices being in different planes. 45 The cutting jet orifice and the main heating jet orifice are also in different planes, according to established practice, and the following or auxiliary heating jet orifice may be in the same plane as the cutting jet orifice. 50 By means of such apparatus, metals of very considerable thickness can be cut, and there is little likelihood of the oxidizing action being interrupted. Furthermore, the consumption of oxygen for cutting may be com-

paratively small. This is because the small 55 auxiliary heating jet following along in the cut reduces or compensates for losses of heat at the seat of operations. At the same time, since all of the jets are in alinement, and since the auxiliary jet is delivered at a lower 60 level than the main heating jet, so that its flame burns within the cut, there is no melting of the metal along the edges of the cut or away from the cut.

The invention also comprises various features of construction as will hereinafter become apparent.

In the accompanying drawings illustrating the apparatus in the form of a hand "torch": Figure 1 is a view partly in section and partly in side elevation of such a torch; Fig. 2 is a longitudinal section through the head and removable tip, illustrating how the operation of cutting a piece of metal is conducted; Fig. 3 is a front end 75 view of the tip; and Fig. 4 is a detail sectional view showing a form of valve that may be employed to control the supply of cutting oxygen.

In the best embodiment of the apparatus 80 the means for delivering the three jets are embodied in the single tip 11, and the gases for the several jets are all supplied to the tip from the common head 12, which holds the removable and replaceable tip. However, 85 it will be understood that as far as the broader aspects of the invention are concerned the passages for leading the gases and discharging the jets may be afforded in any other manner, so long as the characteristic relation between the jets is preserved.

In the specific and novel form of apparatus illustrated, the tip is provided with a central bore or passage 13 for cutting oxygen, the passage terminating in an orifice at 95 the outer end of the tip, and with two other longitudinal bores 14 and 15 for the heating mixture at opposite sides of the oxygen passage and terminating at the outer end of the tip in orifices at opposite sides of the cutting 100 jet orifice. Thus, all of the jet orifices are in alinement. The orifices and passages 14 and 15 are of unequal diameter, the passage 14 for delivering the main or forward heating jet being larger than the passage 15 for 105 delivering the auxiliary or following heating jet. The orifices 13 and 14 are in different planes, and so also, according to the

present invention, are the orifices 14 and 15. As shown, the orifices 13 and 15 may be in the same plane. This may be accomplished by providing the end of the tip with a projection 16 through which the passages 13 and 15 are extended; or, conversely, the end of the tip may be cut back at the region of the passage 14.

The tip 11 is shown as formed of one piece, and such is the preferred construction, but this may be otherwise. The rear end of the tip and the socket 17 in the head 12 are suitably formed to afford a tight sealing joint. For this purpose, I prefer to make use of a conical joint, the angle of which is sufficiently abrupt to insure that the tip cannot stick in the head irrespective of the degree of pressure with which they are forced together, as by means of the coupling 30. The tip is shown as provided with an external conical surface 18 of ample length, and the socket in the head is formed with a corresponding internal surface against which the conical part of the tip seats so as to produce an absolutely tight joint. This particular form of sealing joint is covered by Patent No. 1,028,166 of June 4, 1912, to J. W. Whitford.

The head 12 is provided with the conduit or supply space 19, which communicates with the rear end of the passage 13 for cutting oxygen, in the tip. The head is also provided with conduits or supply spaces 20 and 21, for oxygen and acetylene, to form the combustible mixture for the heating jets. These are common sources of supply for the two heating jets; but in the preferred construction each heating jet has its own complement of passages for bringing about mixing of the two kinds of gases. To this end the tip 11 is provided with separate oxygen and acetylene inlets to each of the passages 14 and 15. In the particular construction illustrated, ports or short passages 14^a and 15^a, in alinement with the passages 14 and 15 and of reduced diameter, serve as inlets for admitting oxygen from the conduit 20 to the rear ends of the passages 14 and 15. Lateral ports or passages 14^b and 15^b in the tip serve to admit acetylene from the conduit 21 to the passages 14 and 15. Thus, each of the passages 14 and 15 constitutes a mixing passage, where the two gases, brought together for the first time in the rear part of the passage, mingle and travel until they are discharged as ignited jets upon the work. These inlets lead from the sealing portion of the tip, which coöperates with the sealing portion of the head to prevent leakage of the gases, so that they cannot improperly mingle with each other or escape through the joint into the air.

Means are provided for placing both passages 14 and 15 in communication with the conduits 20 and 21, and for preserving the

communication even though the tip be turned or rotated in the head. To this end I provide annular communication-establishing channels or spaces; and preferably these channels are formed on the outside of the 70 conical portion of the tip, as shown at 22 and 23. The ports or inlet passages 14^a and 15^a lead from the channel 22, and the ports or inlet passages 14^b and 15^b lead from the channel 23.

The head 12 may be of any suitable construction, and may take on a variety of forms according to the style of apparatus in which the invention is embodied. For purposes of illustration I have shown the head 80 as forming part of a hand torch. The three pipes 24, 25 and 26, for cutting oxygen, oxygen for the heating jets, and acetylene, respectively, together with the chamber 37, designed to contain packing through which the 85 acetylene is passed, form a convenient handle. Conduits 25 and 26 are provided with suitable valves 27 and 28, and the pipe 24 is preferably provided with a spring-closed valve 29. The pipes are provided at their 90 rear ends with suitable couplings for the attachment of flexible tubes leading from the primary sources of supply.

In operation, the apparatus is advanced along the line of the proposed cut, with the 95 larger and more remote heating jet in the lead, and the smaller and closer heating jet in the rear, as indicated by the arrow in Fig. 2. In this view, the letter A indicates the uncut portion of the metal which the 100 oxidizing jet is attacking, and B the portion of the cut already formed. As shown in this view, the main heating jet is set back so that it plays upon the surface of the uncut metal which the cutting jet will presently operate upon. The small auxiliary heating jet is delivered at a lower plane so that it enters immediately into the cut. In this position it can best serve its function of aiding the oxidizing jet, and at the same 110 time it is prevented from melting the edges or corners of the cut. Its small size, also, insures that it will not injure the cut. I find that with this division of the heating gases into two jets of unequal sizes at opposite sides of the cutting jet, the consumption of these gases is economical, and the efficiency of the cutting operation is high. By this I mean that the cutting will proceed without interruption, heavy pieces may 115 be cut cleanly and without much loss of metal, and the consumption of oxygen for cutting is very economical. By my process and apparatus cutting may be performed faster than heretofore. Another very important advantage is that the slag is kept fluid so that it is carried out freely by the oxygen jet. For this reason exceptionally clean cuts may be effected, and the speed is improved because there is no tendency for 120 125

the slag to close up and therefore the apparatus may be advanced as rapidly as the oxidation will proceed.

The oxygen and acetylene for heating are 5 preferably supplied under pressure, and the cutting oxygen usually under greater pressure. The pressure of the cutting oxygen must vary according to the thickness of the metal.

10 While, for purposes of simpler illustration, I have shown the apparatus in the form of a hand torch, it will be understood that the head may be supported and moved by mechanical means, without in any way 15 affecting the invention.

Having thus described my invention, what I claim as new, and desire to secure by Letters Patent, is:

1. Apparatus for cutting metals by means 20 of gases, having means for delivering an oxidizing jet, and two heating jets of unequal sizes and both composed of a mixture of combustible and combustion-supporting gases, with the heating jet orifices in different planes and at opposite sides of the oxidizing jet orifice, the smaller heating jet being closer to the work, substantially as described.

2. A torch for cutting metals by means of 30 gases, having means for delivering an oxidizing jet, separate heating jet passages at opposite sides of the oxidizing jet, each jet passage being provided with separate inlets for combustible and combustion-supporting 35 gases, and common means in the torch for supplying such gases to the inlets of both passages.

3. Apparatus for cutting metals by means 40 of gases, comprising a head, and a removable and replaceable tip having a longitudinal passage for oxygen for cutting, and separate longitudinal passages for heating mixture, each of these latter passages having 45 separate inlets in the rear part of the tip for oxygen and for a combustible gas, said head being provided with conduits for supplying the cutting passage and said inlets.

4. A removable and replaceable tip for apparatus for cutting metals by means of gases, formed at its rear end for sealing engagement with a suitable head, and having a longitudinal passage for cutting oxygen and separate longitudinal passages for heating mixture, each of these latter passages having separate inlets in the sealing portion 55 of the tip for admitting oxygen and a combustible gas from the head.

5. Apparatus for cutting metals by means of gases, comprising a head having separate conduits for oxygen and for a combustible 60 gas, and a removable and replaceable tip having a longitudinal passage for oxygen for cutting, longitudinal passages at opposite sides thereof for heating mixture, annular channels at the rear arranged to communicate at all times with conduits in the head for oxygen and combustible gas, and communications between these channels and the passages for heating mixture.

6. A removable and replaceable tip for 70 apparatus for cutting metals by means of gases, having a member of a sealing joint formed on its rear portion, and being provided with a longitudinal passage for delivering a jet of oxygen, said passage leading from the rear end of the tip, two longitudinal passages at opposite sides thereof of different diameter for delivering heating jets of different sizes, the latter passages terminating in orifices in different planes, and the 80 orifice of larger diameter being farther back toward the source of supply than the orifice for cutting oxygen, the tip being provided in its sealing portion with inlets for admitting oxygen and combustible gas to said 85 passages of unequal diameter.

In witness whereof I have signed my name in the presence of two subscribing witnesses.

WORTHY C. BUCKNAM.
